UNITED STATES PATENT OFFICE.

JULIUS HERRIET, OF NEW YORK, N. Y., ASSIGNOR TO DAVID WOLFE
BRUCE, OF SAME PLACE.

DESIGN FOR A FONT OF PRINTING-TYPE.

SPECIFICATION forming part of Design No. 13,870, dated April 24, 1883.

Application filed March 23, 1883. Term of patent 14 years.

To all whom it may concern:

Be it known that I, JULIUS HERRIET, of New York, in the county of New York, State of New York, (assignor to DAVID WOLFE 5 BRUCE,) have invented and produced a new and original Design for a Font of Printing-Type, of which the following is a specification.

The nature of my design is clearly shown in 10 the accompanying typographic impression, to which reference is made; and it consists of an unshaded letter of the class known as "medieval." The up and down portions of the letter are provided at the top and bottom 15 with the terminations having the inclined sides, as shown in the A, B, H, I, K, M, N, P, R, U, V, W, X, and Y, while the C, D, E, G, O,

Q, S, T, and 2 are provided or made up of the series of inclined lines, as shown. The A and H are crossed centrally by the two inclined lines. The B, M, R, and W are ornamented by the loop having the inclined sides, as shown.

In the symbol and the lower case and the numerals the character of the design is pre- 25 served.

Having now described my invention, I claim as new—

The design for a font of printing-type, as shown and described.

JULIUS HERRIET.

In presence of—

WILLIAM V. H. HICKS,
A. SIDNEY DOANE.
